UNITED STATES PATENT OFFICE.

REUBEN D. CULVER, OF VEEDERSBURG, INDIANA.

DESIGN FOR A PAVING-BLOCK.

SPECIFICATION forming part of Design No. 34,349, dated April 9, 1901.

Application filed January 21, 1901. Serial No. 44,226. Term of patent 14 years.

To all whom it may concern:

Be it known that I, REUBEN D. CULVER, of the city of Veedersburg, Fountain county, State of Indiana, have invented and produced a new and original Design for a Paving-Block, of which the following is a full, clear, and exact description, reference being had to the accompanying drawings, forming a part hereof.

Figure 1 is a perspective view showing my complete design. Fig. 2 is a side elevation.

As shown, the material or essential feature of my design consists of a rectangular body 1, in one of the vertical faces of which are two horizontal grooves 2, dividing the face of the block into three substantially equal divisions, of which the central division projects farther from the body of the block than do the side divisions. The grooves 2 are joined

by vertical grooves 3, and in each of the side divisions near the edge of the block is a horizontal groove 4. The opposite vertical face of the block consists of an upper division 5 and the lower division 6, between which is a central division 7, adapted to contain the inventor's name in elevation. A horizontal groove 9 is in each of the divisions 5 and 6 near the edge of the block.

I claim—

The design for a paving-block, substantially as herein shown and described.

In testimony whereof I affix my signature in presence of two witnesses.

REUBEN D. CULVER.

Witnesses:

ALFRED A. EICKS,
EDWARD E. LONGAN.
